UNITED STATES PATENT OFFICE

2,429,873

SAFETY WINDOW LOCK

Elmer B. Evans, Los Angeles, Calif.

Application March 9, 1945, Serial No. 581,808

1 Claim. (Cl. 292—182)

1

My present invention, in its broad aspect, has to do with improvements in window or sash locks, and more particularly, it is my purpose to use a friction locking member to engage an element of the window frame, and a cam lever for moving the friction element in engagement with the frame, and spring means for releasing the lock when the cam lever is moved to an inoperative position. Furthermore, I provide a lock for both the lower and upper sash, the lock for the upper sash being countersunk, and my lock is simple, sturdy, practical and easily mounted on a conventional window sash and has no parts which are likely to bind or stick, or become broken or deranged or out of order.

Other and equally important objects and advantages of my invention will be apparent from the following description and drawings, and it is to be understood that changes in form, size, shape, materials, and construction and arrangement of parts is permissible and within the purview of my broad inventive concept and the scope of the appended claim.

In the drawings wherein I have illustrated a preferred form of my invention:

Figure 1 is an elevation, partly fragmentary of my lock applied to a lower sash;

Figure 2 is a section on the line 2—2 of Figure 1;

Figure 3 is a section on the line 3—3 of Figure 1;

Figure 4 is a top plan view of my lower sash lock with the cover plate removed to show the operating parts;

Figure 5 is a section on the line 5—5 of Figure 1;

Figure 6 is an elevation, partly broken away, to show my upper sash lock applied;

Figure 7 is a plan view of my upper sash lock with the cover removed to show the working parts;

Figure 8 is a section on the line 8—8 of Figure 6, and

Figure 9 is a section on the line 9—9 of Figure 6.

In the drawings wherein like characters of reference are used to designate like or similar parts:

The numeral 1 designates a window frame and 2 the stop strip, while 3 and 4 designate the upper and lower sash respectively, each having side rails 5. The window and sash are of conventional construction.

Mounted on the side rail 5 of the lower sash 4 to engage the stop strip 2 is my sash lock 6 which has a casing 7 formed with a flat base section 8 with a long flange 9 on one side edge and a short flange 10 on the other side edge, these flanges being bent to form edge locking lips 11 engaging in recesses 12 in the side walls of the top cover plate 13 which has an open front and back end. The casing is held in place on the side rail 5 by screws 14. The operating parts are mounted on the base section 8, and include an arcuate locking foot 15 having a serrated or toothed edge 16 to

15 engage the stop strip 2—this may be rubber covered as at 16a if desired—and is rotatably held in place by a rivet 17 passing through the plate 18 and having a square head 19. The foot has an upstanding lug 20 engaged by a spring 21 which has a straight portion 22 passing through a slot 23 in upstanding flange 24 on the plate 18 to engage a rivet 25 on which is rotatably mounted a cam lever 26, the cam element 27 of which bears against the flange 24 of plate 18 to move the foot into and out of engagement with the stop strip 2. The plate has an attaching lug 28 engaging in a slot in the base section 8. In operation, the foot is normally returned to inoperative position by the spring 21 but is cammed to a locking position by the lever 26.

20 The casing 29 of my upper sash lock is similar to the casing of the lower sash lock, but it is countersunk as shown in Figures 8 and 9 in the sash rail to lie flush with the surface thereof. An angular camming plate 30 has an operating lever 31 passing through a slot 32 in the cover plate and is movable to engage the angular camming end 33 of the plate 34 for actuating the foot which 25 engages the adjoining window frame—see Figure 8—instead of the stop strip 2.

20 From the foregoing, it is believed that the operation and advantages of my invention will be apparent, but it is again emphasized that interpretation of its scope should only be conclusive when made in the light of the subjoined claim.

I claim:

35 A window lock, comprising a casing, an arcuate locking foot, a plate on the casing on which the foot is pivotally mounted, the plate having an upstanding end flange a vertical slot in said flange, a camming lever, a rivet pivotally mounting the camming lever in the casing, a spring passing through the slot in said flange to engage 40 the pivot for the foot at one end and the rivet at the other, and the camming lever movable to engage the flange on the plate to urge the plate and foot into locking position against the tension of the spring, a slot formed in said casing underlying said plate and a lug on said plate for engagement in said slot to prevent lateral displacement of said plate.

ELMER B. EVANS.
